DRIVING AND COMPENSATING MECHANISM
FOR RELATED CONVEYERS

David R. Horwitz, Sheboygan, Wis., assignor to
Hayssen Manufacturing Company, Sheboygan,
Wis., a co-partnership consisting of William A.
Hayssen, Jane P. Hayssen, and Marie Hayssen
Perry

Application November 16, 1939, Serial No. 304,715

1 Claim. (Cl. 198—203)

This invention relates to improvements in driving and compensating mechanism for related conveyers.

Although the present invention may have utility in various fields, it has special utility in bread slicing and wrapping machines and will therefore be described in connection therewith. A bread slicing and wrapping machine usually comprises a slicing mechanism, and a wrapping mechanism. A conveyer carries successive loaves of bread to and through the slicer, and another conveyer receives the successive sliced loaves from the slicer and delivers the same to the wrapping mechanism. Each of said conveyers is provided with moving flights, and it is desirable to have the flights on the wrapper conveyer more widely spaced apart than the flights on the slicer conveyer, because the wrapper conveyer is driven at a greater speed than the slicer conveyer in order to quickly move the sliced loaves away from the blades of the slicer. It is of course obvious that the wrapper conveyer and slicer conveyer should be synchronized relative to one another in order that the pockets between the flights on the former will be correctly located for the reception of loaves from the slicer. Another factor to be considered is that the wrapper conveyer sometimes is run rearwardly, and as the slicer conveyer is driven from the wrapper conveyer it would also then run backwards unless the mechanism contains special means to prevent it. Rearward movement of the slicer conveyer should be guarded against as the flights of the same will not clear the frame members at the conveyer ends in that direction of travel.

In the patent to Creech No. 2,056,134 there is disclosed a bread slicing and wrapping machine wherein the two conveyers may be synchronized. However, in this patent the synchronizing can only be accomplished through movements of the slicer conveyer. Also, this patent contains no provisions for positively and automatically preventing reverse or rearward movements of the slicer conveyer.

With the above points in mind an object of the present invention is to provide a driving and compensating mechanism for related conveyers wherein reverse movements of the wrapper or discharge conveyer may be accomplished without affecting the slicer or incoming conveyer.

A further object of the invention is to provide a mechanism of the character described which provides for the ready synchronizing of a pair of related conveyers, such synchronizing

being attainable not only by manual movements of the incoming conveyer, but also by reverse movement of the discharge conveyer while the incoming conveyer remains stationary.

A further object of the invention is to provide a mechanism of the character described in which an infinite number of positions of one conveyer relative to the other may be obtained for compensating or synchronizing purposes.

A further object of the invention is to provide a driving and compensating mechanism for related conveyers wherein synchronization of the two conveyers may be accomplished without the necessity of stopping the entire machine and while the discharge conveyer is operating.

A further object of the invention is to provide a driving and compensating mechanism for related conveyers which will permit disconnection of the slicer conveyer relative to the wrapper conveyer with the result that the wrapping machine and its conveyer may be operated independently.

A further object of the invention is to provide a driving and compensating mechanism for related conveyers which is of very simple construction, which is easy to install in a bread slicing and wrapping machine, which is easy to operate and control, which is strong and durable, and which is well adapted for the purposes described.

With the above and other objects in view the invention consists of the improved driving and compensating mechanism for related conveyers, and its parts and combinations as set forth in the claim, and all equivalents thereof.

In the accompanying drawings in which the same reference characters indicate the same parts in all of the views:

Fig. 1 is a fragmentary view from one side of the related conveyers of a bread slicing machine with parts broken away and in section;

Fig. 2 is a plan view of the portion of the machine shown in Fig. 1, with parts broken away and in section;

Fig. 3 is a fragmentary sectional view of the side opposite to that shown in Fig. 1 of that portion of the machine which includes the driven and controlled shafts for the incoming or slicer conveyer, said view being taken on line 3—3 of Fig. 2;

Fig. 4 is an enlarged fragmentary view, partly in section, of a portion of the wrapper conveyer shaft which carries a clutch mechanism; and

Fig. 5 is a transverse sectional view taken on line 5—5 of Fig. 4.

A bread slicing machine, with which the pres-

ent improvements may, by way of illustration, be associated, includes an upright frame or housing 10 within which there are spaced, reciprocating knives for loaf slicing purposes. A delivery table 11, having suitable side rails 12 associated therewith, extends toward one side of the slicer housing 10. Spaced loaves to be sliced are propelled along the table 11 in the direction of the arrow in Fig. 1 by means of an endless conveyer. Said endless conveyer includes laterally spaced-apart chains 13 extending over sprockets at the forward end of the machine (not shown) and also extending over sprockets 14 and 14' at the intermediate portion of the machine, the sprockets 14 being mounted fast on a driven shaft 15. Carried by the chains at suitable intervals are flights 16.

At the inner end of the table 11 there is an inclined extent 17 leading to the slicing mechanism. When loaves or other objects are passed through the slicer they are successively received on the inner end of a discharge conveyer table 18. Associated with said table is a discharge or wrapping conveyer formed of laterally spaced-apart chains 19 which carry spaced, transverse flights 20. The flights of the wrapper conveyer are more widely spaced apart than are the flights of the slicer conveyer because the wrapper conveyer travels at a greater rate of speed than the slicer conveyer, as will hereafter appear. The outer ends of the chains 19 extend about the sprockets on a driven shaft (not shown), this being conventional in machines of this type and the shaft is driven directly from some source of power such as the wrapping mechanism. In other words the chains 19 of the wrapper conveyer are positively driven and extend over sprockets 21 on a shaft 22 at the intermediate portion of the machine. For the purposes of this invention said shaft 22 may be considered as a driving shaft and power to propel the incoming conveyer is derived therefrom, as will appear hereinafter.

On one end portion of the shaft 22 there is mounted a one-way, overrunning clutch designated generally by the numeral 23. This clutch is shown in detail in Figs. 4 and 5 and includes a cupped member 24 whose hub portion 24' is pinned to said shaft, as at 25. A sleeve 26 surrounds a portion of said shaft inwardly of the cupped member 24 and the portion of said sleeve within the cupped member is formed as an integral wheel 27 with a plurality of eccentric pockets 28 therein. Within each pocket of the wheel and confined by the inner wall of the cupped member 24 there is a roller bearing 29. When the roller bearings are in the enlarged portions of the pockets the same may roll freely and the members 24 and 26, and all members respectively connected thereto, may have revolute movement relative to each other. If relative movement of the members 24 and 26 is in a direction to urge the rollers toward the reduced ends of the pockets 28, then the rollers will become bound and cause an engagement as between the members 24 and 26 whereby the same can only turn together in one direction. The sleeve 26 and parts integral therewith are actually loose on the shaft 22 and only become fast on the shaft when the sleeve 26 is engaged with the cupped member 24 through the binding of the rollers, as previously mentioned. An inner portion of said sleeve 26 also has fast thereon a small sprocket wheel 30.

Referring now to the inner end portion of the frame of the slicer or incoming conveyer, it will

be observed that there is suitably journalled therein, forwardly of and slightly above the shaft 15, a control shaft 31. One end portion of said shaft 31 has fast thereon a large sprocket wheel 32, which sprocket wheel is connected with the sprocket 30 on the shaft 22 by means of an endless chain 33. The end portion of the shaft 31 which carries the sprocket wheel 32 extends inwardly through suitable bearings 34 and an intermediate portion of the shaft has loose thereon a gear 35. Between a face of the gear and the innermost bearing a spring 36 is coiled about the shaft. Formed integrally with the other face of the gear is a disk 37 having a reduced portion 38. Also on the shaft 31 adjacent the disc 37 is a collar 39 which is pinned to the shaft and which is provided with a notch or recess 40 to disengageably receive a tooth or lug 41 on the adjacent face of the disc 37.

Longitudinally movably mounted transversely in the frame of the incoming conveyer below the shaft 31 is a shifting rod 42 carrying a handle 43 at one end. Fast on an intermediate portion of said rod 42 there is an upstanding yoke 44 extending adjacent the reduced portion 38 of the disc 37 and adapted to bear against face portions of the members 35 or 37. If the rod 42 is pushed inwardly said yoke 44 will move the members 35 and 37 on the shaft 31 sufficiently far to disengage the lug 41 from the recess 40, this movement being against the force of the spring 36. With this movement the gear 35, although still in mesh with a gear 46, will be free on its shaft and will be an idler. When the rod 42 is released the spring 36 will return the members to the position shown, whereupon the gear 35 will be fast with the shaft, through the medium of the pinned collar 39, and will be driven by the shaft.

The numeral 45 designates an intermediate or counter-shaft also journalled transversely in the frame of the incoming conveyer and positioned between the shafts 31 and 15. A gear 46 is mounted fast on an intermediate portion of said shaft and it meshes with the gear 35 on the shaft 31. A scroll or eccentric gear 47 is mounted fast on an end portion of the counter shaft 45 and said gear meshes with a similar scroll gear 48 fast on the driven or main shaft 15 of the incoming conveyer. By means of said scroll or eccentric gears the incoming conveyer is caused to run alternately slow and faster to accelerate movements of the same at desired periods. Under any conditions, however, the speed of travel of the incoming conveyer is less than that of the discharge conveyer, as previously mentioned.

Having in mind the specific details of construction heretofore described, the operation of the improved mechanism will now be taken up. When the device is used in association with a bread slicing machine, as illustrated, it is obvious that the successive loaves of bread to be sliced are propelled along the table 12 by means of the flights 16 and are delivered into and through the reciprocating knives in the slicer housing 10. The successive sliced loaves then reach the inner end of the delivery table 18 and are propelled therewith by the flights 20 carried by the chains 19 of the discharge conveyer. Presumably the sliced loaves may be delivered to some other instrumentality as a wrapping machine.

For the mechanism which forms the subject of the present invention the discharge conveyer chains 19 may be considered as the drivers as they are connected with some other source of

power. The upper extent of the chains 19 normally travel in the direction of the arrow in Figs. 1 and 2 and this will cause the discharge conveyer shaft 22 to revolve in a clock-wise direction relative to Figs. 1, 2, 4 and 5. The shaft 22 carries the overrunning one-way clutch 23 previously described and with the shaft 22 revolving in the direction referred to the sprocket wheel 30 will be driven with the shaft in the same direction due to the clutch engagement of the parts. This motion will be effective to drive the large sprocket wheel 32 on the shaft 31 of the incoming conveyer, through the medium of the connecting chain 33. Normally the disc 37 is engaged with the collar 39 on the shaft 31 so the gear 35 will be driven by the shaft 31 transmitting, through the gear 46, rotation to the countershaft 45. By virtue of the meshing scroll gears 47 and 48 on the shafts 45 and 15 respectively, rotation in a clock-wise direction, relative to the referred to views of the drawings, is imparted to the shaft 15. As before mentioned the scroll gears cause the shaft to revolve alternately slow and fast. The shaft 15 carries the driving sprockets 14 for the incoming conveyer chains and hence the incoming conveyer is driven at the desired speed relative to the discharge conveyer and it is propelled by the movement of the discharge conveyer through the connections referred to. This operation is the normal operation of the mechanism and of course when the power for the discharge conveyer is shut off both the discharge conveyer and the incoming conveyer will stop.

Under certain conditions it is desirable to move the flights 20 of the discharge conveyer in a reverse direction and for this purpose the power for the discharge conveyer is reversed. Then the shaft 22 will turn in a counterclockwise direction relative to Figs. 1, 2, 4 and 5. At this time the clutch 23 becomes effective to provide disengagement as between the sprockets 30 and the driven shaft 22. When the shaft 22 turns in the reverse direction the sprocket 30 will remain stationary and will not drive the chain 33 which leads to the sprocket 32 on the shaft 31. It will therefore be seen that through the provision of the clutch 23 the drive between the shaft 22 and the shafts of the incoming conveyer will be broken upon reverse movement of the discharge conveyer. This is particularly desirable and necessary in certain forms of mechanisms of which the present device is an example for the reason that the conveyer members and flights of the incoming conveyer are designed to only travel in a forward direction and provision is therefore made to positively prevent reverse movement of the incoming conveyer, notwithstanding reverse movement of the discharge conveyer, which is the normal driving instrumentality. It may also be pointed out that reverse movement of the discharge conveyer may be necessary and desirable when it is desired to synchronize, compensate or adjust the location of the flights of the discharge conveyer relative to the position of the flights of the incoming conveyer. This may be necessary when the machine is used for a series of packages of different sizes than those for which it was originally set.

Some times, in the operation of the entire mechanism, it may be desirable to disconnect the

incoming conveyer from the discharge conveyer so far as driving is concerned. This may be important when it is desired to use only the discharge conveyer of the machine for delivering unsliced goods to a wrapper, for instance. In this event the handle 43 of the shifting rod 42 is manipulated whereby the gear 35 is disconnected from the collar 39 and becomes an idler. Then, motion will not be transmitted to the incoming conveyer shaft 15 and the incoming conveyer will not be moved notwithstanding continuing movement of the discharge conveyer.

In addition to the manner of obtaining synchronization or compensation as between the two conveyers previously described and effected by running the discharge conveyer in a reverse direction a desired distance, compensation or synchronization can be accomplished through manually turning the incoming conveyer shaft 15. A hand wheel 49 on an outer end of the shaft 15 may be manually turned in the direction of the arrow in Fig. 2, to thereby move the conveyer chains 13 and relocate the flights 16 of the incoming conveyer. Although turning movement is imparted to the shaft 31 through the gears 46 and 35, the shaft 22 of the wrapper conveyer will not be turned because the overrunning clutch 23 comes into play and prevents the driving of said shaft 22. This mode of compensation or synchronization can be accomplished without the necessity of shutting off the power for the machine including the discharge conveyer.

From the foregoing explanation of the various modes of operation of the mechanism it will be apparent that reverse movements of the discharge conveyer can be accomplished for any desired reason, and for the purposes of compensation, without affecting the incoming conveyer. Also, several practical methods of easy synchronization may be accomplished with this mechanism and the positions of adjustment are unlimited. The improved mechanism is further of simple and novel construction and is well adapted for the purposes described.

What is claimed as the invention is:

Regulating mechanism associated with a pair of related, different speed conveyers, one of the conveyers being a driver and the other conveyer being driven therefrom and the first conveyer including a driving shaft and the second conveyer including a driven shaft, comprising motion transmitting means connecting said shafts, an overrunning clutch incorporated in the driving shaft of the first conveyer for automatically effecting a driving connection for said motion transmitting means upon forward movement of the driving conveyer and a disconnection of said motion transmitting means upon a rearward movement of the driving conveyer, said motion transmitting means including a shaft adjacent the driven shaft of the second conveyer with driving connections between said shafts, manually operable means for engaging and disengaging the driving connections as between said last two mentioned shafts, and a hand operated member on said driven shaft for turning it in a predetermined direction to obtain compensating advancement of the second conveyer relative to the first conveyer.

DAVID R. HORWITZ.
